US0D1060044S

(12) **United States Design Patent** (10) Patent No.: **US D1,060,044 S**
Willard et al. (45) Date of Patent: ** Feb. 4, 2025

(54) **CONTAINER**

(71) Applicant: **PetSmart Home Office, Inc.**, Phoenix, AZ (US)

(72) Inventors: **Zachary Parker Willard**, Phoenix, AZ (US); **Gregory J. Costanzo**, Scottsdale, AZ (US)

(73) Assignee: **PETSMART HOME OFFICE, INC.**, Phoenix, AZ (US)

(**) Term: **15 Years**

(21) Appl. No.: **29/889,351**

(22) Filed: **Apr. 11, 2023**

Related U.S. Application Data

(63) Continuation of application No. 29/856,265, filed on Oct. 12, 2022, and a continuation of application No. 29/856,263, filed on Oct. 12, 2022.
